UNITED STATES PATENT OFFICE.

CHARLES D. McDONALD, OF CHICAGO, ILLINOIS.

ATTACHMENT FOR THE FEED-BARS OF DIE-PRESSES OR THE LIKE.

1,252,278.

Specification of Letters Patent.

Patented Jan. 1, 1918.

Application filed February 23, 1917. Serial No. 150,447.

To all whom it may concern:

Be it known that I, CHARLES D. McDONALD, a citizen of the United States, residing at Chicago, in the county of Cook and State 5 of Illinois, have invented certain new and useful Improvements in Attachments for the Feed-Bar of Die-Presses or the like, of which the following is a specification.

The present invention relates to an attachment 10 adapted to be used in connection with the automatic feed-bar or feed-mechanism of die-presses or the like, and which will operate so as to stop the movement of all operative portions of the press should the feed-bar encounter an interference to its normal movement.

One object of the invention is to provide a means for breaking the power connection between the drive-shaft and the operative 20 portions of the press whenever an obstruction is encountered by the feed-bar which prevents the normal movement thereof, whereby a continuing operation of the die and associated parts of the press after the 25 feed of the work is stopped, is eliminated, and the danger of wear and tear, and often-times serious injury to the press, is avoided.

A further object of the invention is to employ a mechanism for carrying out the 30 above purpose which will be capable of use in connection with a feed-mechanism, using a releasable connection between the feed-bar and the part for operating the same.

A further object of the invention is to 35 employ a shiftable means which will be actuated upon stoppage of the feed-bar, and to arrange a connection between such shiftable means and certain clutch and brake mechanism so that upon operation of the shiftable means, further communication of power 40 from the drive-shaft to the operative portions of the press is cut off.

The invention further consists in the features of construction and combination of 45 parts hereinafter described and claimed.

In the drawings:

Figure 1 is a side view of a die-press body, showing the means for operating the feeding-mechanism, and showing the device of 50 the present invention in operative position;

Fig. 2, a detail front view, showing the feed-bar and its connection, together with the attachment of the present invention, and with the parts in the position they assume 55 during the normal operation of the feed-bar:

Fig. 3, a view similar to Fig. 2, showing the parts in the position they assume when the feed-bar encounters an obstruction preventing its normal movement, and with the feed-bar released from its operating member and the attachment of the present invention moved so as to set the mechanism which breaks the connection between the power-shaft and the operating portions of the press;

Fig. 4, a view of the mechanism which makes and breaks the connection between the power-shaft and the operative portions of the press, and showing such connection in released position, which is the position assumed when a connection is being maintained between the drive-shaft and operative portions of the press;

Fig. 5, a view similar to Fig. 4, showing the parts in the position assumed when the connection between the drive-shaft and operative portions of the press is broken;

Fig. 6, a detail showing a front view of the parts shown in Figs. 4 and 5;

Fig. 7, an enlarged front view of the clutch and brake mechanism;

Fig. 8, a detail face view of the clutch mechanism;

Fig. 9, a detail, partly in section, of the clutch mechanism; and

Fig. 10, a detail showing one of the arms which actuate the clutch mechanism.

In connection with automatic die-presses, a reciprocating feed-mechanism in the form of a bar is generally employed for moving the work step by step into operative position below the die plunger. Owing to irregularities in the work, or a misplacement of the work during the feeding operation, the work becomes jammed in the feed way, and upon a continued operation of the feed-bar, necessarily a condition arises which is detrimental to the machine and requires a stoppage of the machine and a partial dismantlement for correction.

In Patent No. 1,039,565, granted September 24, 1912, to C. D. McDonald, for metal working machines, there is shown a releasable attachment between the feed-bar and the crank-arm, which operates said bar, whereby when the bar encounters a strain or impediment which interferes with its normal operation, the connection between the feed-bar and crank-arm pulls apart, so that the feed-bar no longer continues to operate. This construction eliminated a great por-

tion of the difficulty in connection with the jamming above set forth, since it prevented the feed-bar from continuing to pound the choked work, and thus increasing the choking of the feed passage. However, this release of the feed-bar resulted only in stopping the operation of the feed-bar. The remainder of the mechanisms of the press continued to operate. The die plunger continued to pound into the female die, often times creating a mutilation of the die or placing a strain on the crank-shaft which operates the die, so that said shaft was bent.

Either of the above conditions, of course, is detrimental and requires replacement of parts, which is not only expensive, by reason of the cost of new parts, but, further, in that the press is put out of service for a greater or less length of time.

20 In the present invention, when a choking of the feed channel is encountered, the feed-bar is not only released from engagement with the crank-arm and its movements stopped, but such releasing operates automatically certain mechanisms which cut off the supply of power from the crank-shaft to the remainder of the operating portions of the press, thus stopping the entire press mechanism and eliminating the damage 25 heretofore referred to, which may result from a continuing of the operation of the remainder of the press mechanism after the feed-bar has ceased to operate.

In the drawings, illustrating one embodiment of my invention, I have shown a press body 11, which may be of any suitable size and style; and mounted in said press body is a main driving-shaft 12. This shaft, as shown, is employed in connection with a reciprocating toggle arm 12' for operating the die plunger. This toggle arm and its method of operation is fully shown in my co-pending application Serial No. 150,445, filed February 23, 1917, and entitled "Apparatus for die-presses or the like," and a detailed illustration and description are not deemed necessary in the present application, particularly in view of the fact that the present invention is deemed to be adaptable 45 for application to presses which may employ a different method than the above for operating the die plunger.

As shown in the drawings, and more particularly in Fig. 1, the crank-shaft 12 operates a gear 13 meshing with a gear 14 on a stub-shaft 15, which stub-shaft also carries a gear 16 meshing with a gear 17 on a stub-shaft 18, on which shaft is also mounted a disk 19. Eccentrically secured to this disk 60 is a rod 20, which, as shown, is pivotally connected to a head 21 mounted in a slot 22 in a rocking lever 23, pivoted at 24. The head 21 is adjustable back and forth in the slot 22 so as to vary the degree of movement imparted by the rod 20 to the lever 23. Con-

nected to one free end of this lever is a fork 25, to which is pivotally secured a head 26 connected to a rod 27. This rod terminates in a head 28, from which extends a sleeve 29 bolted or otherwise secured to a flange 30 on a rocking arm 31 (see Figs. 1, 2 and 3). This rocking arm is pivoted to swing upon a pin 32, and its end 33 is entered between spring jaws 34 held normally closed by means of a spring 35 on a stem 36 (see Figs. 75 2 and 3). The jaws 33 and 34 are carried by a link 37, pivotally connected at 38 to a head 39, adjustably connected to a feed-bar 40 operating with a reciprocating movement in a feed channel within a casing 41.

The tension of the spring 35 is such that when the feed-bar encounters an impediment to its normal movement within the feed channel, as by a jamming of the work within said channel, the end 33 of the crank arm 31 will pull out from between the jaws 34, breaking the connection between the crank arm and the feed-bar and stopping further movement of said bar.

The foregoing connection between the feed-bar and crank-arm is disclosed in my issued Patent No. 1,039,565, of September 24, 1912, and heretofore referred to. No claim is made to this construction in the present case, other than may be in combination with the particular parts which relate to the present invention.

As previously explained, while the disconnecting of this feed-bar from the crank-arm will stop the operation of the bar, it will have no effect in stopping the operation of the remainder of the press mechanisms, and the present invention deals with the creation of a mechanism for stopping the application of power through the main drive-shaft to the balance of the press mechanisms when normal movement of the feed-bar is prevented by jamming of the work, etc.

To carry out this automatic stopping in the construction shown, I employ a link 42 pivotally connected by a pin 43 to the arm 37. The link 42 has a slot 44 in its lower end, in which rests a pin 45 on an arm 46, which is pivotally mounted upon a pin 47. The arm 46 has extending therefrom flanges 48, in the nature of a fork, and between which passes the stem 49, having an abutment 50 on one end, and formed upon its opposite end with a head 51 connected to an arm 52, which is keyed or otherwise secured to a cross-shaft 53.

To the opposite end of the cross-shaft 53 is secured a lever 54 provided with a suitable hand grip (see Figs. 4 and 5). This lever is limited, as shown, in its up and down movements by means of adjustable stops 55. Connected to the lever 54 is a link 56 joined to a rocking lever 57, one end of which latter lever is connected to a rod 58, which operates a brake spreader 59.

To the opposite end of the lever 57 is connected a rod 60 joined to a bell-crank 61, to which is connected a link 62 joined to a clutch-actuating arm 63. This arm, at its lower end, is connected to a link 64, and this link is also joined to a clutch-actuating arm 65, pivoted at 66. These arms 63 and 65 are best illustrated in Figs. 8, 9 and 10, and each embodies a cam or wedge-shaped face 67, which is adapted to enter beneath a clutch pin 68 and force said pin outwardly, breaking the clutch connection from the drive-shaft to the remainder of the machine.

The clutch pin enters into a recess in a collar 69 on a fly-wheel 70, and it is through this collar and pin that the connection is made from the fly-wheel to that portion of the drive-shaft that operates the press mechanisms. This form of clutch is one well adapted for use with the toggle die-plunger operation described in my co-pending application heretofore referred to; but it is understood that this form of clutch is only shown for the purpose of illustrating one form 25 adapted for use in connection with the present invention, since, of course, a variety of styles of clutches might be employed, and particularly so if the die plunger should be operated by means other than the toggle arms.

The clutch illustrated is one which will act when the crank-shaft turns a half revolution after the clutch-actuating arms are set, owing to the presence of a clutch arm on each side of the shaft. This form of clutch is desirable with presses in which the die plunger is actuated by toggle mechanism, since, when so actuated, there are two strokes of the die plunger to each revolution of the 40 crank-shaft, and by arranging the clutch so that it will set when a half revolution is completed, the clutch will act to stop the machine when the die plunger reaches the limit of its up-stroke.

It is to be noted that by reason of the various links and levers employed, the movement from the link 42 to the brake spreader and clutch-actuating arms is amplified, so that these latter parts are enabled to perform their functions without undue strain being placed on the initial movable parts.

The operation briefly is as follows:

When an obstruction is encountered in the feed channel, the resistance exerted on the feed-bar will arrest the movement of the latter, causing the end of the crank-arm 31 to pull out from the jaws 34. The arm 37 will then fall by gravity, pushing downward the link 42, and the pin 45, through engagement 60 with the end of the slot 44, will be forced downward, pushing down the arm 46 and pulling down the rod 49, as in Fig. 3. This downward movement of the rod 49 will pull the free end of the arm 52 downward, rocking the shaft 53, and causing the lever 54

to swing from the position of Fig. 4 to that of Fig. 5. This pushes up the link 56, as in Fig. 5, rocking the lever 57, as in said figure, and moving the rods 58 and 60, the movement of the rod 58 causing the brake spreader 59 to assume the position in Fig. 5, whereby a spring acts to close the brake members.

The movement of the rod 60 actuates the bell-crank 61 and link 62 to throw the clutch arm 63 inward, and through the link 64 moves the clutch arm 65 inward, bringing the wedge faces of said clutch arms into the position whereby one or the other engages the pin 68, moving it out of its recess within the hub 69 of the fly-wheel, and breaking the connection to the main drive-shaft. This stops the entire press mechanisms and eliminates any danger of damage through the plunger and other press mechanisms continuing to operate after the feed-bar has stopped.

To reset the machine, the crank-arm 31 is placed back in the position shown in Fig. 2, so that it is connected once more to the arm 37 and adapted to actuate the feed-bar. The lever 54 is then thrown from the position shown in Fig. 5 to that shown in Fig. 4, which rocks the lever 57 into the position shown in Fig. 4, moving the rod 58 to expand and release the brake and moving the rod 60 to pull the clutch-actuating arms outward, so that their wedge faces are free from engagement with the pin 68; and this pin then drops in the recess within the hub of 100 the fly-wheel and the machine again starts operating.

I claim:

1. In mechanism of the class described, the combination of feed means, power driven 105 means for actuating the feed means, means for controlling the application of power to said power driven means, and means for actuating said power controlling means to stop the application of power to said power 110 driven means when said feed means encounter an abnormal resistance to their normal movement, substantially as described.

2. In mechanism of the class described, the combination of feed means, power 115 driven means for actuating the feed means, means for controlling the application of power to said power driven means, shiftable means for actuating said power controlling means and adapted to shift when said feed 120 means encounter an abnormal resistance to their normal operation, said shiftable means when so shifted moving the power controlling means to cut off the application of power to said power driven means, substantially as described.

3. In mechanism of the class described, the combination of feed means, power driven 125 means for actuating the feed means, a releasable connection between the feed means

and the power driven means adapted to release when the feed means encounter an abnormal resistance to their normal movement, means for controlling the application 5 of power to said power driven means, and means actuated by the breaking of said releasable connection for moving the power controlling means and cutting off the application of power to said power driven 10 means, substantially as described.

4. In mechanism of the class described, the combination of feed means, power driven means for actuating the feed means, a releasable connection between the feed 15 means and power driven means adapted to release when the feed means encounter an abnormal resistance to their normal movement, means for controlling the application of power to the power driven means, shiftable means for actuating the power controlling means and shifted by the breaking of said releasable connection, and when so shifted actuating said power controlling means to cut off the supply of power to said 20 power driven means, substantially as described.

5. In mechanism of the class described, the combination of feed means, power driven means for operating the feed means, 30 means for controlling the application of power to said power driven means, shiftable means for operating said power controlling means and adapted to shift when said feed means encounter an abnormal resistance to their normal movement, a cross-shaft, a connection between said cross-shaft and said shiftable means, and a connection between the cross-shaft and the means for controlling the application of power, whereby said shiftable 35 means when shifted operate the power controlling means to cut off the application of power from said power driven means, substantially as described.

6. In mechanism of the class described, 45 the combination of feed means, power driven means for operating the feed means, means for controlling the application of power to said power driven means, means for actuating said power controlling means, said actuating means moving by gravity when the feed means encounter an abnormal resistance to their normal movement and when so moved actuating said power controlling means to cut off the application of 55 power to said power driven means, substantially as described.

7. In mechanism of the class described, the combination of feed means, power driven means for actuating the feed means, 60 a releasable connection between the feed means and power driven means adapted to release when the feed means encounter an abnormal resistance to their normal move-

ment, a member moving by gravity when said connection is broken, and means actuated by said movement of said gravity operated member for cutting off the application of power to said power driven means, substantially as described. 65

8. In mechanism of the class described, 70 the combination of feed means, power driven means for actuating the feed means, means for controlling the application of power to said power driven means, a releasable connection between the feed means 75 and power driven means adapted to release when the feed means encounter an abnormal resistance to their normal movement, a member moving by gravity when said connection is released, a cross-shaft rocked by the movement of said gravity actuated member, a connection between the power controlling means and cross-shaft, whereby said controlling means are operated when said shaft is rocked to cut off the application of power 80 to said power driven means, substantially as described.

9. In mechanism of the class described, the combination of feed means, power driven means for operating the feed means, 90 means for controlling the application of power to said power driven means, shiftable means for operating said power controlling means shifting when the feed means encounter an abnormal resistance to their 95 normal movement, a connection between the shiftable means and power controlling means actuating when the shiftable means are shifted to cut off the application of power to said power driven means, and said 100 connection being arranged to amplify the movement from said shiftable means to said power controlling means in transmitting movement between these parts, substantially as described. 105

10. In mechanism of the class described, the combination of feed means, power driven means for operating the feed means, means for controlling the application of power to said power driven means, shiftable 110 means for operating said power controlling means and shifting when said feed means encounter an abnormal resistance to their normal movement, a series of links and levers connecting said shiftable means and said power controlling means, said shiftable means when shifted actuating said link and lever connection to move the power controlling means and cut off the application of power to said power driven means, and said connection serving further to amplify the movement of the shiftable means in transmitting such movement to the power controlling means, substantially as described. 115 120

CHARLES D. McDONALD.
